CLAIM

The ornamental design for a flat cooking panel, as shown and described.

DESCRIPTION

FIG. 1 is a perspective front and side view of the flat cooking panel of the invention;

FIG. 2 is a plan view thereof;

FIG. 3 is a front elevational view thereof; and

FIG. 4 is a left side elevational view of FIG. 3, the right side elevational view being a mirror image thereof.

FIG.1

FIG.2
